UNITED STATES PATENT OFFICE.

FRANK L. McCONNELL, OF ASTORIA, ILLINOIS.

SAW-SETTING TOOL.

1,263,447.

Specification of Letters Patent. Patented Apr. 23, 1918.

Application filed October 7, 1916. Serial No. 124,367.

To all whom it may concern:

Be it known that I, FRANK L. McCONNELL, a citizen of the United States, residing at Astoria, in the county of Fulton and State of Illinois, have invented certain new and useful Improvements in Saw-Setting Tools, of which the following is a specification.

This invention relates to plier instruments, 10 and particularly to saw sets.

It is the primary object of the present invention to provide a saw set which embodies the advantageous features of setting instruments now generally in use, and which has 15 its operating handles so constructed and arranged as to enable the operator to assume a more natural and comfortable position while working upon a saw. A further object is to provide a saw setting instrument which 20 has the handles for operating the setting plunger so positioned or arranged as to develop the greatest amount of power with a relatively low degree of manual exertion.

With the above objects in view, together 25 with others which will appear as the description proceeds, the invention resides in the novel formation, combination and arrangement of parts, all as will be described more fully hereinafter, illustrated in the 30 drawings, and particularly pointed out in the claims.

In the drawings:—

The figure represents a side elevation of 35 a saw setting tool constructed in accordance with the invention in the act of operating upon a saw tooth.

Referring now more particularly to the drawings, 5 indicates a conventional form of saw clamp, between the jaws of which is secured a saw blade indicated at 6, and in position to be conveniently operated upon.

The set illustrated in the present instance is of the spring plunger type, and comprises a fixed jaw portion 7 for engagement over 45 the tooth of a saw, and which carries adjusting blocks 8 and 9 for purposes familiar to those intimate with devices and work of this character. The tooth engaging and bending plunger is indicated at 10, and is 50 mounted for sliding movement into and out of the jaw portion, and is held normally retracted by an expansion coil spring 11.

Formed with the head or jaw portion 7 and at the rear end thereof is a stationary 55 or fixed handle portion or grip 12, the latter being extended at substantially right an-

gles to the direction assumed by the head. Pivoted as at 13 upon the fixed handle 12 and adjacent the juncture of the latter with the head, is the strain lever or handle 14. This 60 movable handle is so positioned upon the fixed member 12 as to engage with the rearwardly protruding end of the bending plunger or pin 10, and is provided with a shallow smooth walled recess 15 in which the 65 rounded end of the pin may engage. The movable handle at its pivoted end overlies the adjacent portion of the fixed handle and carries a laterally extending pin 16 disposed beyond the point of connection of the movable handle with the fixed handle, and is adapted to engage the head to limit the outward swinging movement of the said movable handle. The fixed and movable handles 12 and 14 are of sufficient length to afford 70 sufficient leverage for the bending or setting operation, and are shaped so as to conveniently and comfortably fit within the hand of the operator.

It will be observed that the stop or pin 16 80 limits the outward swinging movement of the lever 14 so as not to permit of the handles being separated beyond the span of the hand, and the spring 11 upon the plunger 10 is of such tensile strength as will cause 85 the latter to operate against the surface 15 to normally maintain the lever 14 at the limit of its outward movement. When the instrument is operated, the forearm of the holder of the device extends substantially at right 90 angles to the handles, so that the position of the arm during the setting operation is natural, and the upper arm may depend from the shoulder socket and lie close to the body. With the arm in this position, it is obvious 95 that greater gripping power with the hand may be had.

In this illustration and description, I have referred to the device as being adapted particularly for use as a saw setting tool, but it 100 is obvious that the inventive characteristics may be equally as well employed in the construction of other metal and wood working tools of the same general nature.

While the present is a disclosure of the 105 preferred embodiment of the invention, it is to be understood that the invention is not necessarily limited thereto, as various changes may be made in the construction, arrangement and proportions of the parts, 110 without departing from the scope of the invention, as defined in the appended claims.

What is claimed is:—

1. The combination with a punching tool including a head having the usual reciprocating plunger, of a handle formed with said head at the rear end thereof and extending at substantially right angles to the said tool, a handle pivoted to said first named handle and being adapted when moved in one direction to operate upon said plunger, 5 the said pivoted handle being adapted to move rearwardly of the fixed handle, and means for yieldably holding said plunger retracted and said handle extended.
2. In a punching tool, a head, a sliding plunger in said head, a handle formed integral with said head at one end and being dis- 10 15

posed at right angles to the said plunger, a second handle pivoted to and overlying the said integral handle above the said plunger and being adapted to move rearwardly 20 of the said integral handle, and a pin carried by said overlying portion and being adapted to engage said head to limit the movement of said pivoted handle in one direction.

25

In testimony whereof I affix my signature in presence of two witnesses.

FRANK L. McCONNELL.
